United States Patent Office

Des. 210,916
Patented Apr. 30, 1968

210,916

PROJECTION VIEWER

Kenneth W. Scott, Rochester, N.Y., assignor to Eastman Kodak Company, Rochester, N.Y., a corporation of New Jersey

Filed Jan. 30, 1967, Ser. No. 5,598

Term of patent 14 years

(Cl. D61—1)

FIGURE 1 is a front perspective view of a projection viewer showing my new design; and

FIGURE 2 is a rear perspective view showing the other side and top thereof.

The bottom of the projection viewer is plain and unornamented.

I claim:

The ornamental design for a projection viewer, as shown and described.
